RAZOR BLADE HONING DEVICE

Felix S. Buba, Detroit, Mich.

Application February 16, 1934, Serial No. 711,528

2 Claims. (Cl. 51—65)

This invention relates to razor blade honing devices and the object of the invention is to provide a honing device for razor blades comprising two movable honing faces slidably mounted in a casing and movable against the edges of a razor blade.

Another object of the invention is to provide a razor blade honing device in which the honing faces may be reciprocated in opposite directions in the casing, means being provided for supporting and turning the razor blade into contact with the honing faces during movement thereof.

Another object of the invention is to provide a razor blade honing device in which sliding movement of one honing face moves the other honing face in the opposite direction.

A further object of the invention is to provide a razor blade holder rotatably mounted between the honing faces and turnable in either direction to bring the opposite edges of the razor blade into contact with the honing faces.

These objects and the several novel features of the invention are hereinafter more fully described and claimed and the preferred form of construction by which these objects are attained is shown in the accompanying drawing in which—

Fig. 1 is a longitudinal section through a razor blade honing device embodying my invention.

Fig. 2 is a plan view thereof with the parts broken away to show the construction.

Fig. 3 is a section taken on line 3—3 of Fig. 1.

The device comprises a sheet metal casing consisting of the upper and lower halves 1 and 2 which are hinged together at 3 as shown in Fig. 1. As shown in Fig. 3, the upper half of the casing is provided with two longitudinal channels 4 in which a block 5 is slidably mounted and these channels may be separate channels as shown or may be formed from the metal casing. The lower half of the casing is provided with two channels 6 in which a block 7 is slidably mounted and a knob 8 is secured to this block and extends through a slot 9 provided in the face of the casing, as shown in Figs. 1 and 3. The honing stone 10 is set into and cemented into the block 5 and a honing stone 11 is set into and cemented in the block 7, as shown in Figs. 1 and 3. A pin 12, shown in Fig. 1, is supported in the upper half 1 of the casing and a sleeve 13 is rotatably mounted on this pin. A flexible fabric strip 14 is secured to the block 5 at 15 and extends over the sleeve 13 and is secured to the block 7 at 16. The block 5, as shown in Figs. 1 and 2, is provided with a recess 17 and a coiled spring 18 is mounted in this

recess and is secured to the block 5 by the screw 19 while a lug 20 is struck inwardly from the upper half of the casing 1 and provides a hook over which the opposite end of the spring 18 is engaged. A lug 21 is also struck out from the metal of the upper part 1 of the casing and a hook 22 is engaged over this lug and is arranged to hook through a loop 23 pressed out from the lower half 2 of the casing. By this arrangement, the two halves of the casing may be hooked together.

Each half of the casing at the dividing line is provided with an extruded semi-circular flange 24, as shown in Figs. 2 and 3 and when the two halves of the casing are locked together these flanges 24 provide circular bearings for the blade holder. The blade holder is formed from two parts, a lower part 25, shown in Fig. 3, and an upper part 26 also shown in the said figure. The part 25 at the end extends into a thimble 27 which is circular in form and a semi-circular member 28 is also positioned in this thimble and provides a socket end 29 to receive the rounded end 30 of the portion 26 of the holder. Through the center the portions of the holder take the form shown in Figs. 1 and 2 and each portion is provided with a rubber face 31 so that a razor blade 32 may be gripped between these faces. At the end opposite the thimble 27 the portions 25 and 26 are cylindrical in form and when assembled form a circular collar 33 while a thimble 34 may be slipped over the outer ends of the parts 25 and 26 to clamp the blade between the portions 25 and 26 of the blade holder. The thimble 27 is provided with a collar 35 and a flat spring 36 is secured to the block 5 and rides in contact with the collar 35. A similar spring 37 is also secured to the block 5 and rides in contact with the collar 33.

In operation the hook 22 is disengaged to allow the halves of the casing to be opened on the hinge 3. At this time the thimble 34 may be removed from the ends of the members 25 and 26 and the member 26 may be lifted up on the pivot 30 to allow the blade 32 to be inserted between the rubber faces 31 of the holder parts.

At this time the part 26 is turned back to the position shown in Fig. 3 and the thimble is slipped over the ends of the parts 25 and 26 to clamp the blade in the holder and the casing parts may be then hooked together. At this time the knob 8 may be moved from the position shown in full lines in Fig. 1 to the position shown in dotted lines in the said figure which will move the block 7 to the left of Fig. 1 and by means of the fabric strip 14

or belt 14 will draw the block 5 to the right of Fig. 1. As the block 5 is moved to the right of Fig. 1 the springs 36 and 37 riding on the collars 35 and 33 will turn the holder in its bearings to bring the blade to the position shown in dotted lines in Fig. 1. This position of the blade occurs as the blocks start their movement and the honing faces of the blocks move against the opposite edges of the blade as will be understood from Fig. 1 thus 10 grinding the edges. After the knob 8 has been moved to the position shown in dotted lines in Fig. 1 it is released and the spring 18 which has been extended by the movement of the block 5 will again draw the block 5 to the left of Fig. 1 15 and by means of the belt 14 will draw the block 7 to the right of Fig. 1. At this time the springs 36 and 37 turn the holder to the position shown in full lines in Fig. 1 thus grinding the remaining opposite edges of the blade. These springs 36 and 20 37 put sufficient pressure on the holder to hold the blade in firm contact with the honing stones and thus it is only necessary to move the knob 8 from the position shown in full lines to that shown in dotted lines in Fig. 1, at which time, it may be 25 released allowing the springs 18 to reverse the operation. After the blade has been positioned in the device it is only necessary to move the knob 8 from the position shown in full lines to that shown in dotted lines and release it several times 30 whereupon the blade is sharpened and ready for use.

While I have shown honing stones for sharpening the blades any fine abrasive surface may be utilized for this purpose and mounted on or applied to the sliding blocks.

From the foregoing description it becomes evident that the device is very simple and efficient in operation, will not easily get out of order, is composed of few parts and is of consequent low 40 manufacturing cost and provides a device which accomplishes the objects described.

Having thus fully described my invention, its utility and mode of operation, what I claim and desire to secure by Letters Patent of the United 45 States is—

1. In a razor blade honing device, a casing comprising two parts hinged together, a block mov-

able longitudinally of each casing part, each block being provided with an abrasive face, a razor blade holder rotatably mounted between the casing parts and arranged to hold a razor blade, a pin extending through one casing part, a flexible strip attached to the blocks and extending over the pin, one casing part being provided with a slot, a knob attached to the respective block and extending through the casing slot, a spring attached at one end to the other block and connected at the other end to the respective casing part, the arrangement being such that longitudinal movement of one block by means of the knob moves the other block in the opposite direction by means of the flexible strip and the spring 10 being arranged for returning the blocks to the original position, a pair of flat springs attached to one of the blocks and riding in engagement with the blade holder, the arrangement being such that movement of the block and flat springs 20 in one direction by the knob turns the blade holder to bring the edges of the blade into contact with the abrasive faces of the blocks and movement of the said blocks in the opposite direction by the spring turns the blade holder in 25 reverse direction to bring the remaining edges of the blade into contact with the abrasive faces of the blocks.

2. In a razor blade honing device, a casing comprising two parts hinged together, a block mov- 30 able longitudinally of each casing part, each block being provided with an abrasive face, a razor blade holder rotatably mounted between the casing parts and arranged to hold a razor blade, a pin extending through one casing part, a flexible 35 strip attached to one block and extending over the pin and attached to the other block, the arrangement being such that longitudinal movement of one block moves the other block in the opposite direction, a spring for returning the blocks to the 40 original position after movement thereof, a pair of flat springs attached to one of the blocks and frictionally engaging the blade holder to turn the blade holder during movement of the blocks to bring the opposite edges of the blade into contact with the abrasive faces of the blocks.

FELIX S. BUBA.
